US0D1087101S

(12) **United States Design Patent** (10) **Patent No.:** **US D1,087,101 S**
(45) **Date of Patent:** **** Aug. 5, 2025**

(54) **CASE FOR ELECTRONIC DEVICE**

- (71) Applicant: **Samsung Electronics Co., Ltd.**, Suwon-si (KR)
- (72) Inventors: **Sol Lee**, Suwon-si (KR); **Namhyun Kang**, Suwon-si (KR); **Minah Koh**, Suwon-si (KR)
- (73) Assignee: **SAMSUNG ELECTRONICS CO., LTD.**, Gyeonggi-Do (KR)
- (**) Term: **15 Years**
- (21) Appl. No.: **29/959,474**
- (22) Filed: **Aug. 26, 2024**

Related U.S. Application Data

- (63) Continuation of application No. 29/902,362, filed on Sep. 12, 2023, now Pat. No. Des. 1,043,699.

(30) **Foreign Application Priority Data**

- Jun. 13, 2023 (KR) 30-2023-0022405
- (51) **LOC (15) Cl.** **14-02**
- (52) **U.S. Cl.**
USPC **D14/440**

(57) **CLAIM**

The ornamental design for a case for electronic device, as shown and described.

DESCRIPTION

FIG. 1 is a front perspective view of a case for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion '9' in FIG. 1; and,

FIG. 10 is an enlarged view of the encircled portion '10' in FIG. 5.

The broken lines in the figures depict portions of the case for electronic device that form no part of the claimed design. The dot-dot-dash broken lines encircling enlarged portions of the claimed design form no part of the claimed design.

1 Claim, 7 Drawing Sheets
